Application April 20, 1945, Serial No. 589,432

7 Claims. (Cl. 173—328)

1

The present invention relates to electrical connectors and, particularly, to such connectors which are adapted to engage an approximately cylindrical conductive contact member. While the invention is of general application, it has particular utility as an electrode terminal connector for use with vacuum tubes of the type having an electrode terminal sealed through, or directly supported by, a wall of an evacuated glass envelope and will be described in that connection.

It frequently is desirable to provide an electrical connector adapted to engage an approximately cylindrical conductive contact member. No essential problem is encountered in a simple connector of this type when the only requirement to be met is that of providing a positive consistent electrical contact with the contact member. However, problems of design arise when the connector must additionally provide adequate and consistent thermal contact with the contact member to enable substantial conduction of thermal energy therebetween and particularly is this true when the force required to effect complete engagement between the contact member and the connector must be minimized. The problems thus raised are multiplied where the connector must at the same time allow for some eccentricity of the contact member and for lateral and angular departures from coincidence of the axes of the contact member and connector.

To illustrate by example the problem encountered in providing an electrical connector of the type described, consider the case of an electrical connector for a vacuum tube of the type having an anode terminal sealed through or supported by one wall of a glass envelope. The power handled by the tube may be sufficiently large that the anode terminal heats so excessively as to fracture the glass seal unless precautions are taken to conduct thermal energy rapidly away from the anode terminal. The anode terminal connector in such case must not only provide the required electrical connection to the anode terminal, but additionally must firmly engage most of surface of the latter and be capable of furnishing a path of low thermal resistance to a thermal-dissipative surface if adequate cooling of the anode terminal is to be effected. This usually presents no undue problem if the anode connector is of split construction adapted to be placed over the anode terminal and clamped thereto. Where, however, it is required that the anode connector be simply slipped bodily over the anode terminal without subsequent clamping, serious problems arise concern-

2

ing the manner of attaining the required firm thermal contact over a large contact area particularly since the force required to effect complete engagement of the connector and terminal cannot be large without danger of fracture of the tube glass envelope.

In many such applications, it is further necessary that the vacuum tube be physically inserted axially into operative position and that, during 10 such insertion, the anode terminal and possibly one or more electrode terminals fully engage fixed electrical connectors provided therefor. The anode terminal in these tubes usually is positioned axially of the tube envelope at the inserted end 15 thereof. It is quite difficult in practice accurately to center and axially to align the anode terminal at the time it is sealed to the glass envelope of the tube. The anode terminal connector consequently must additionally be capable of permitting small lateral and angular departures 20 from coincidence of the axes of the terminal and connector without placing undue strain on the terminal since this strain would be transmitted directly to the glass seal and would tend to 25 fracture it.

It is an object of the present invention therefore to provide a new and improved electrical connector adapted to engage an approximately cylindrical conductive contact member.

It is a further object of the invention to provide 30 a new and improved electrical connector, adapted to engage an approximately cylindrical conductive contact member, having greater thermal conductivity than has readily been heretofore obtainable in a connector of the type described.

It is an additional object of the invention to provide 35 an electrical connector, adapted to engage an approximately cylindrical conductive contact member, of improved and relatively inexpensive construction.

It is another object of the invention to provide 40 a new and improved electrical connector, adapted to engage an approximately cylindrical conductive contact member, which ensures positive, consistent and substantially uniform electrical and thermal contact with such contact member while minimizing the force required to effect complete engagement of the contact member with 45 the connector and, at the same time, permitting relative lateral and angular departures from coincidence of the axes of the contact member and connector.

In accordance with one form of the invention, 50 an electrical connector, adapted to engage an

approximately cylindrical contact member, comprises stacked laminations of resilient conductive material having nested V-shaped contact fingers arched normal to the plane of lamination and extending radially with respect to a common axis to provide at their inner ends a cylindrical laminated contact surface normally symmetrical about such common axis but deformable to maintain coincidence of the axis of the contact surface with that of the contact member when the latter is positioned in engaging relation with the contact surface. The connector is thus adapted to ensure consistent and substantially uniform electrical and thermal contact with the contact member while minimizing the force required to effect complete engagement of the member with the connector.

For a better understanding of the present invention, together with other and further objects thereof, reference is had to the following description taken in connection with the accompanying drawings, and its scope will be pointed out in the appended claims.

Referring now to the drawings, Fig. 1 illustrates a high-frequency wave-signal oscillator which utilizes electrical connectors embodying the present invention; Fig. 2a is an enlarged cross-sectional side view of a portion of the electrical connector of the present invention, while Fig. 2b is a top view of the stacked laminations thereof; and Fig. 3 illustrates a method of forming the connector laminations.

Referring now more particularly to Fig. 1 of the drawings, there is illustrated a high-frequency wave-signal oscillator which utilizes electrical connectors embodying the present invention. This oscillator is disclosed and claimed in a copending application of Harold A. Wheeler, entitled Ultra-short-wave signal-translating device, Serial No. 565,828, filed November 30, 1944, and assigned to the same assignee as the present application. Reference is made to this copending application for a detailed description of the oscillator and its mode of operation. Briefly, the oscillator includes a first or anode cavity resonator 10 and a second or cathode cavity resonator 11 which is capacitively coupled to the resonator 10 by a probe 12 arranged to extend through an aperture 13 in a diaphragm 14 separating the cavity resonators 10 and 11. The cavity resonator 10 includes a cylindrical hollow outer conductor 15 and a cylindrical hollow inner conductor 16 which are maintained in fixed coaxial relationship by insulating spacers 17 secured between the conductors 15 and 16 at points suitably spaced around the circumference thereof. One end of the inner conductor 16 is closed by a disc 18 which forms one element of an electrical connector 20 embodying the present invention and presently to be described in greater detail. Briefly considered for purposes of the present description, the disc 18 has a centrally positioned concentric aperture with a concentric shoulder 18a upon which is secured by machine screws 18b a stack of laminations 19 more fully described hereinafter. The outer conductor 15 of the cavity resonator is closed at its end opposite the diaphragm 14 by a disc 21 which supports, in coaxial relation with the conductor 15, a cylindrical conductor 22 of diameter appreciably smaller than that of the inner conductor 16. The conductor 22 effectively forms a re-entrant portion of the outer conductor 15 and is used for purposes of tuning the resonator 10.

The second or cathode resonator 11 similarly

includes an outer hollow cylindrical conductor 15', which may be an extension of the conductor 15, and an inner hollow cylindrical conductor 23 which is supported by a conductive ring 24 in coaxial relation with the outer conductor 15'. A conductive ring 25 is positioned between and electrically engages the inner and outer conductors 23 and 15', this ring being adjustable axially along these conductors for purposes of tuning the cathode cavity resonator. The end of the inner conductor 23 adjacent the diaphragm 14 is closed by a disc 26 having a centrally positioned coaxial aperture and forming an element of an electrical connector 27 similar in construction to that of the electrical connector 20. The diaphragm 14 likewise has a centrally positioned coaxial aperture in which is secured an electrical connector 28 of a type disclosed and claimed in applicant's copending application entitled Electrical connector, Serial No. 571,610, filed January 6, 1945, and assigned to the same assignee as the present application.

A vacuum tube 29 has an approximately cylindrical conductive contact member or anode terminal 30 hermetically sealed to one end of a cylindrical glass envelope portion 31, a conductive grid terminal disc 32 which is hermetically sealed between the envelope portion 31 and a second cylindrical glass envelope portion 33, and a conductive cathode terminal 34 sealed to one end of the glass envelope portion 33. The tube 29 is insertable axially through the center of the hollow conductor 23 of the cathode cavity resonator 11 into operative position with its anode terminal 30 engaging the electrical connector 20, its grid terminal disc 32 engaging the electrical connector 28 and its cathode terminal 34 engaging the electrical connector 27. For purposes of simplicity, certain electrical connectors which extend out of the flat base of the tube 29 are not shown nor is the means shown for maintaining tube 29 in the operative position described.

Reference is made to the aforementioned copending Wheeler application for a detailed description of the oscillator described. Briefly considered, oscillations developed in the cathode cavity resonator 11 are repeated by the vacuum tube 29 to the anode cavity resonator 10 and a portion of the oscillatory energy developed in the latter is applied by the probe 12 back to the cathode cavity resonator 11 to maintain sustained oscillation of the oscillator.

During operation of the oscillator, it is necessary that the anode terminal 30 of the tube 29 be electrically connected by the electrical connector 20 through the disc 18 thereof and the inner conductor 16 of the anode cavity resonator 10 to a source of anode potential indicated as +B. The vacuum tube 29 during operation translates sufficient power that the temperature of the anode terminal 30 is raised to a high value. There is consequently danger of fracturing the glass seal between the anode terminal 30 and the tube envelope portion 31 unless thermal energy is conducted rapidly away from the anode terminal. Hence, it is necessary that the electrical connector 20 make good thermal contact with the anode terminal 30 over a major portion of the surface of the latter and that the connector provide a path of good thermal conductivity to the conductor 16 in order that the latter may act as thermal radiators to maintain the anode terminal 30 at a relatively low safe temperature.

An additional requirement of the electrical connector 20 is that it must accommodate eccen-

tricities of the anode terminal 30 and permit relative departures from coincidence of the axes of the anode terminal and the connector while the vacuum tube 28 is in its operative position in the oscillator and also during insertion and withdrawal thereof. Otherwise a mechanical strain is placed upon the anode terminal 30 which may fracture the seal between the anode terminal and the tube envelope portion 31. For a like reason, the electrical connector 20 must minimize the force required to effect complete engagement and disengagement of the anode terminal 30 with the connector.

Certain of the requirements last mentioned with relation to the electrical connector 20 apply, though to a lesser degree, to the electrical connectors 27 and 28.

Considering now in greater particularity the portion of the oscillator arrangement described which embodies the present invention, a portion 20 of the electrical connector 20 is illustrated in enlarged cross-sectional side view in Fig. 2a and in top view in Fig. 2b. The connector, which as heretofore explained is adapted to engage the approximately cylindrical conductive contact member 30, comprises stacked laminations 19 of resilient conductive material having nested V-shaped contact fingers 35 arched normal to the plane of lamination and extending radially with respect to a common axis o—o to provide at their inner ends a cylindrical laminated contact surface S normally symmetrical about the common axis o—o but deformable to maintain coincidence of the axis of the contact surface S with that of the contact member 30 when the member is positioned in engaging relation with the surface S. The material of the laminations 19 may, for example, be beryllium copper and each lamination preferably is silver-plated to reduce the resistance of the connector for high-frequency wave signals. The connector includes ring-shaped spacing laminations 36 inserted between the laminations 19 at the outer ends of the contact fingers 35. It is the purpose of the spacing laminations 36 to maintain the laminations 19 slightly spaced along the entire lengths of the contact fingers 35 to permit increased conjoint flexibility of the laminations at the inner ends of the fingers so that the latter, over a limited range of movement, may flex individually. Each of the laminations 19 is formed of sheet material having a concentric indentation 37 of V-shaped cross section, normal to the plane of lamination, formed in one face thereof, as by a rolling, spinning or stamping operation, to a depth much greater than the thickness of the lamination. As more clearly shown by the top view of the Fig. 2b, each of the laminations 19 has an aperture 38 centrally positioned with relation to the indentation 37 and concentric with the axis o—o of the connector. The contact fingers 35 are formed by serrating the laminations 19 radially with respect to the axis o—o to a radial depth approximately equal to the outer diameter of the indentation 37. A relatively rigid ring 39, shown more clearly in Figs. 2a and 2b, preferably is used to maintain the laminations 19 firmly clamped in assembled relation.

Fig. 3 illustrates a suitable method by which the laminations 19 are formed. Starting with a flat disc of conductive material, the concentric groove 37 is first stamped into one face of the material while at the same time the central portion, indicated by the broken-line portion 40, of the disc is pressed upwardly above the face of the

disc. The central portion 40 of the disc is now punched out to provide the central aperture 38 and the disc is then slotted radially by a sawing or punching operation to provide the contact fingers 35. It will be apparent that while these steps have been described as successive steps in the formation of the lamination, one or more such steps may be combined into a single step. For example, the serrations may be formed by the same die which punches out the central portion 40 of the lamination.

It is preferable as a finishing step of the connector construction that the laminations 19 be stacked in assembled relation and the central aperture 38 be then ground or lapped to a diameter slightly smaller than that of the contact member with which the connector is used. This ensures the maximum area of contact surface of the ends of the fingers 35 with the contact member and at the same time removes any burrs which may be formed at the inner ends of the contact fingers during one or more of the forming steps previously described. Alternatively, the contact surface S of the connector may be brushed with a steel-wire brush rotating about the axis o—o of the laminations. This brushing operation serves primarily to remove any burrs at the inner ends of the contact fingers.

Where the connector of the present invention is used to engage the anode terminal of a vacuum tube as in the particular application hereinbefore described, it is preferable that the aperture 38 of the connector have a diameter a few thousandths of an inch smaller than the diameter of the anode terminal in order that the laminations at the inner ends of the contact fingers 35 may flex over a limited range of movement as individual laminations substantially out of contact with one another. This reduces to a very minimum the force required to make and to break contact of the anode terminal with the connector while yet ensuring adequate and consistent thermal and electrical contact therebetween. In an actual embodiment of this type, the difference in diameters of the aperture 38 and the anode terminal member was made of the order of 0.005 to 0.010 inch.

If the end of each contact finger of an individual lamination lies substantially in the plane defining the roots of the serrations of the lamination and if the aperture 38 is only slightly smaller than the contact member as just described, there is perhaps minimum tendency of the contact fingers 35 to oppose axial movement of the contact member in either direction through the connector. For some applications, it may be desirable to so form the contact fingers that the ends of the fingers of each individual lamination extend a few thousandths of an inch above the plane defining the roots of the serrations of the lamination since this introduces a very slight locking effect against withdrawal of the contact member from fully engaged relation with the connector. In the actual embodiment last mentioned, the contact fingers were so formed that the ends thereof extended 0.30 inch above the plane of the serration roots.

It will be apparent from the above description of the invention that an electrical connector embodying the invention provides positive, consistent and substantially uniform electrical and thermal contact with a cylindrical contact member when the latter is in engaging relation therewith. There is the further advantage that the force required to effect complete engagement

of the contact member with the connector is minimized while, at the same time, relative lateral and angular departures from coincidence of the axes of the connector and contact member are permitted. There is the additional advantage that the electrical connector is of relatively simple and inexpensive construction and is well adapted to mass production techniques.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An electrical connector adapted to engage an approximately cylindrical conductive contact member comprising, stacked laminations of resilient conductive material having nested V-shaped contact fingers arched normal to the plane of lamination and extending radially with respect to a common axis to provide at their inner ends a cylindrical laminated contact surface normally symmetrical about said common axis but deformable to maintain coincidence of the axis of said contact surface with that of said contact member when said member is positioned in engaging relation with said surface, whereby said connector is adapted to ensure consistent and substantially uniform electrical and thermal contact with said contact member while minimizing the force required to effect complete engagement of said member with said connector.

2. An electrical connector adapted to engage an approximately cylindrical conductive contact member comprising, stacked laminations of resilient conductive material having nested V-shaped contact fingers arched normal to the plane of lamination and extending radially with respect to a common axis to provide at their inner ends a cylindrical laminated contact surface normally symmetrical about said common axis but deformable to maintain coincidence of the axis of said contact surface with that of said contact member when said member is positioned in engaging relation with said surface, and means for spacing said laminations at the outer ends of said contact fingers to permit increased conjoint flexibility of said laminations at the inner ends of said fingers, whereby said connector is adapted to ensure consistent and substantially uniform electrical and thermal contact with said contact member while minimizing the force required to effect complete engagement of said member with said connector.

3. An electrical connector adapted to engage an approximately cylindrical conductive contact member comprising, stacked laminations of resilient conductive material having nested V-shaped contact fingers arched normal to the plane of lamination and extending radially with respect to a common axis to provide at their inner ends a cylindrical laminated contact surface normally symmetrical about said common axis but deformable to maintain coincidence of the axis of said contact surface with that of said contact member when said member is positioned in engaging relation with said surface, and spacing laminations inserted between said first-mentioned laminations at the outer ends of said contact fingers to permit increased conjoint flexibility of the inner ends of said fingers, whereby

said connector is adapted to ensure consistent and substantially uniform electrical and thermal contact with said contact member while minimizing the force required to effect complete engagement of said member with said connector.

4. An electrical connector adapted to engage an approximately cylindrical conductive contact member comprising, stacked laminations of resilient conductive material having nested V-shaped contact fingers arched normal to the plane of lamination and extending radially with respect to a common axis to provide at their inner ends a cylindrical laminated contact surface normally symmetrical about said common axis but deformable to maintain coincidence of the axis of said contact surface with that of said contact member when said member is positioned in engaging relation with said surface, a mounting member having a surface for supporting said laminations at the outer ends of said contact fingers, and means for securing said laminations to said mounting member to provide a unitary connector structure, whereby said connector is adapted to ensure consistent and substantially uniform electrical and thermal contact with said contact member while minimizing the force required to effect complete engagement of said member with said connector.

5. An electrical connector adapted to engage an approximately cylindrical conductive contact member comprising, a plurality of laminations each of resilient conductive sheet material having integrally formed contact fingers arched to have a V-shaped configuration normal to the plane of lamination and extending radially with respect to a common axis, said laminations being stacked with said contact fingers in nested relation to provide at the inner ends of said fingers a cylindrical laminated contact surface normally symmetrical about said common axis but deformable to maintain coincidence of the axis of said contact surface with that of said contact member when said member is positioned in engaging relation with said surface, whereby said connector is adapted to ensure consistent and substantially uniform electrical and thermal contact with said contact member while minimizing the force required to effect complete engagement of said member with said connector.

6. An electrical connector adapted to engage an approximately cylindrical conductive contact member comprising, a plurality of laminations of resilient conductive sheet material each having a central aperture with radial serrations extending therefrom to provide a plurality of integrally formed contact fingers arched to have a V-shaped configuration normal to the plane of lamination and extending radially with respect to a common axis, said laminations being stacked with said contact fingers in nested relation to provide at the inner ends of said fingers a cylindrical laminated contact surface normally symmetrical about said common axis but deformable to maintain coincidence of the axis of said contact surface with that of said contact member when said member is positioned in engaging relation with said surface, whereby said connector is adapted to ensure consistent and substantially uniform electrical and thermal contact with said contact member while minimizing the force required to effect complete engagement of said member with said connector.

7. An electrical connector adapted to engage an approximately cylindrical conductive contact member comprising, a plurality of laminations

each of resilient conductive sheet material having a ring indentation of V-shaped ring section formed in one face thereof to a depth much greater than the thickness of said lamination and having an aperture centrally of said indentation with radial serrations extending therefrom to provide a plurality of integrally formed V-shaped contact fingers arched in a direction normal to the plane of laminations and extending radially with respect to a common axis, said laminations being stacked with said contact fingers in nested relation to provide at the inner ends of said fingers a cylindrical laminated contact surface normally symmetrical about said common axis but deformable to maintain coincidence of the axis of said contact surface with that of said contact member when said member is positioned

in engaging relation with said surface, whereby said connector is adapted to ensure consistent and substantially uniform electrical and thermal contact with said contact member while minimizing the force required to effect complete engagement of said member with said connector.
